UNITED STATES PATENT OFFICE.

JOHN H. GAULT, OF PHILADELPHIA, PENNSYLVANIA.

DESIGN FOR A BOTTLE.

SPECIFICATION forming part of Design No. 24,468, dated July 16, 1895.

Application filed January 16, 1895. Serial No. 535,151. Term of patent 14 years.

To all whom it may concern:

Be it known that I, JOHN H. GAULT, a citizen of the United States, residing at Philadelphia, in the county of Philadelphia and State of Pennsylvania, have invented a certain new Design for Bottles; and I do hereby declare the following to be a full, clear, and exact description of the same.

My invention relates to designs for bottles. The characteristic feature of the same is a bottle in the shape of a human tooth surrounded by a projecting neck, with a representation of a widely-open mouth upon one side of the bottle.

The design is clearly illustrated in the accompanying drawing, in which the figure thereof represents a perspective view of a bottle formed according to my design. In

this it will be seen that the body portion 1 is formed in the shape of a human tooth with an ordinary neck 2 at the top. On the sides of the bottle is represented the design of an open mouth with a full set of teeth 4 projecting from each jaw and the lips 5 of the mouth.

Having thus described the invention, what is claimed as new is—

The design for a bottle, as herein described and shown.

In testimony whereof I have signed this specification in the presence of two subscribing witnesses.

JOHN H. GAULT.

Witnesses:

D. S. LINDSAY,
DORA LANDAU.
